United States Patent Office

Des. 180,927
Patented Sept. 10, 1957

180,927

GAS BURNER UNIT

Chester S. Binasik, San Francisco, Calif., assignor to Coen Company, San Francisco, Calif., a corporation of California

Application July 17, 1956, Serial No. 42,275

Term of patent 14 years

(Cl. D81—2)

Fig. 3.

Fig. 2.

Fig. 1.

Fig. 1 is a front elevational view of a gas burner unit showing my new design;

Fig. 2 is a side elevational view thereof; and

Fig. 3 is a top plan view thereof.

I claim:

The ornamental design for a gas burner unit, as shown.
